UNITED STATES PATENT OFFICE.

RANDALL T. VAN VALKENBURG, OF MANCHESTER, MICHIGAN.

MORTAR-MIXING MACHINE.

SPECIFICATION forming part of Letters Patent No. 257,627, dated May 9, 1882.

Application filed March 15, 1882. (No model.)

To all whom it may concern:

Be it known that I, RANDALL T. VAN VALKENBURG, of Manchester, in the county of Washtenaw and State of Michigan, have invented new and useful Improvements in Mortar-Mixing Machines; and I do hereby declare that the following is a full, clear, and exact description thereof, reference being had to the accompanying drawings, which form a part of this specification.

The nature of this invention relates to certain new and useful improvements in the construction of that class of machines which are designed for mixing plasterers' mortar; and the invention is especially designed to be an improvement upon the device patented to Charles Pierce, August 19, 1873, in Letters Patent No. 141,947, and which now belongs to me.

The invention consists in the peculiar construction of parts, their various combinations and operation, as more fully hereinafter described.

Figure 1 is a perspective view of my improved machine, taken on one side. Fig. 2 is a perspective view taken from the rear of the machine. Fig. 3 is a similar view taken from the opposite end. Fig. 4 is a central longitudinal section through the lime-slaking cylinder, its hollow shaft, and connections. Fig. 5 is a sectional view, showing the construction of the regulating cut-off between the elevators and the mixer proper.

In the accompanying drawings, A represents the frame of my machine, which supports the operating parts. This frame may be varied from the construction shown, as may be desired. A box, B, divided into two parts by the partition-wall is supported by the frame. Journaled above one of the chambers, so as to discharge its contents into said chamber, is the rotating sand screen C', which is given its rotary motion from any convenient power. This screen is open at the center of its ends, as shown in Fig. 2, and a chute, D, is provided, into which sand is to be shoveled and discharged into the screen. Above the other chamber of this box B is a rotating cylinder, E, secured to a hollow perforated shaft, F, which rotates in bearings or boxes a, secured to the frame. This cylinder is provided with a door or slide, b, through which the lime to be slaked is shoveled in and withdrawn.

G is a tank or source of water-supply, provided with a rigid pipe, c, in which is a cock or regulating-valve, d. The unconnected end of this pipe is provided with a conically-shaped mouth, e, to receive the end of the shaft F, which is properly shaped to fit into said mouth, and some suitable device—like the spring H, impinging against the opposite end of said shaft—is employed to prevent lateral play thereof and to compel a tight connection with the water-supply without interfering with the rotation of the shaft, upon which is secured a pulley, h, by means of which the shaft may be rotated from any suitable power. The pulley h is so secured to the shaft as to rotate with it, while at the same time it is susceptible of a reciprocating movement on the shaft, being actuated thereto by the lever i and forked lever k, in the usual manner of operating a clutch. One face of the pulley is so constructed as to form one half of the clutch, while the other half thereof is secured to the adjacent head of the cylinder E, as shown in Fig. 1. Below this cylinder is a flat screen, o, through which the contents of the cylinder, when discharged therefrom, pass into the box. Each of the chambers of this box B is provided with a trap or door, l, through which the contents of the box are discharged into an annex, I, from which they are carried by the two-part elevator, one being for each division or chamber of the annex, which is divided into two compartments coincident to the chambers in the box B by the partition m. The sand being screened falls into one of these chambers, while the stones and lumps found in the sand are discharged from the screen through the spout n, which is situated at the end of the screen opposite the chute. The lime is put into the cylinder E through the door b, which is then closed, and the water let into the hollow shaft escapes through the perforations therein into the lime, which, in the rotation of the cylinder, becomes finely slaked. The pulley-clutch may then be disengaged and the slaked lime discharged through the door b onto the screen o, which arrests any stones and allows the fine slaked lime to pass into its proper chamber. The elevators carry up the contents of the box, one elevator carrying the lime and the other the sand, and dumps the sand into the hopper J and the

lime into the other hopper, J' . Below each of these hoppers there is a revolving cylinder, K , suitably journaled upon trunnions s , running in bearings upon the supports t . The interior of each of these cylinders is provided with two radial partitions, u and u' , the former being stationary and the latter movable by means of the pins or buttons v , which project through the head or end of each of these cylinders in order to enlarge or diminish the area of the V-shaped chamber L in the cylinders. The wall of each of these cylinders is cut out, the opening being of the same area as the discharge ends of the hoppers J J' . These cylinders are so journaled below the hoppers as to act as a cut-off to prevent discharge from said hoppers, except when the opening in the cylinders, in their rotation, is presented to the discharge end of the hopper, when the chambers in said cylinders are filled by such discharge. In the further rotation of the cylinders they cut off further discharge until the next revolution, and discharge their contents into the mixing-chamber M , through which passes the main driving-shaft of the device, said shaft being provided with mixing-blades N , arranged spirally upon the shaft, or in such a manner that as they revolve they not only mix the lime and sand together, but carry the mixture toward the rear end of the mixing-chamber, where it passes into the top of a spout, P , within which revolves a solid wheel, R . The lower end of this spout is enlarged to form a semicircular concavity, within which the wheel R rotates almost in contact with the concave of the spout, so that the mixed mortar, as it passes down the spout, will be ground to a uniform fineness before it passes down to the discharge of the concave. This spout, with its wheel, is fully described in the patent hereinbefore referred to. The opening in the mixing-chamber is provided with a slide or door, S , through which the mixed mortar passes to the spout.

45 A belt, T , communicates motion to the wheel R from the main shaft. Upon the opposite end of this main shaft are secured pulleys U , one being larger than the other two, and communicates motion, by means of the belt or cord V , to the cylinder E and rotating screen C' , while the smaller of the pulleys communicates motion to the small cylinders K by means of

the belt or cord W , and the third pulley U , by means of a belt or cord, X , (shown in Fig. 1,) communicates motion to the pulley Y , which carries the conveyers Z , and are journaled upon the shaft running in the top of the standards A' . By this system of belting all the rotating parts are driven from the main shaft and are compacted into a very small compass.

What I claim as my invention is—

1. In a device for the purpose described, the combination, within the frame A , of the rotating screen C' , the cylinder E , and the screen o , with the chambered box B , substantially as specified.

2. In a mortar-mixing device, and in combination, the rotating screen C' , cylinder E , subdivided box B , provided with openings l , and the subdivided annex I , adapted to deliver the contents to elevators, substantially as and for the purposes described.

3. In a mortar-mixing machine provided with devices for screening the sand, slaking the lime, and elevating the same to the hoppers J and J' , the cylinders K , constructed and operating substantially as and for the purposes set forth.

4. In a mortar-mixing machine, the cylinder E , provided with a hollow and perforated shaft, in combination with the rigidly-secured water-supply pipe c , such hollow shaft rotating within the head of said pipe and secured in its rotation so as to form a water-tight joint by pressure upon the opposite end of such shaft, substantially as and for the purposes set forth.

5. In a mortar-mixing machine, substantially as described, and in combination, the rotating screen C' , cylinder E , box F , annex I , and elevators Z , the latter being adapted to take the contents of the annex I and deliver them into the hoppers J and J' , substantially as set forth.

6. The combination, in a mortar-mixing machine inclosed within the same supporting-frame and driven from a single main shaft, of the sand-screen, lime-slaking cylinder, receiving-box, elevating devices, hoppers, graduated cut-offs, and mixing-chamber, the parts constructed, arranged, and operating substantially as and for the purposes described.

RANDALL T. VAN VALKENBURG.
